FOOD CONTAINER

Charles Alfred Bernheiser, Reading, Pa., assignor to
W. R. Grace & Co., Duncan, S.C.

Filed Jan. 13, 1972, Ser. No. 217,721

Term of patent 14 years

Int. Cl. D9—03

U.S. Cl. D9—182

FIG. 1

FIG. 2

FIG. 3

FIG. 4

FIG. 5

FIG. 6

FIG. 7

FIG. 1 is a top perspective view of a food container embodying my new design;

FIG. 2 is an elevational view looking from the right of FIG. 1;

FIG. 3 is an elevational view looking from the left of FIG. 1;

FIG. 4 is an elevational view on an enlarged scale looking from the front of FIG. 1;

FIG. 5 is a top plan view of FIG. 1;

FIG. 6 is a bottom plan view of FIG. 1; and

FIG. 7 is a top plan view on a still larger scale than FIG. 4 showing the design in an open position.

I claim:

The ornamental design for a food container, substantially as shown.
